CLAIM

The ornamental design for a display screen with graphical user interface, as shown and described.

DESCRIPTION

FIG. 1 is a front view of a display screen with graphical user interface showing our new design;

FIG. 2 is a second embodiment thereof; and,

FIG. 3 is a third embodiment thereof.

The broken line showing portions of the graphical user interface in FIG. 1 form part of the claimed design. Broken lines showing portions of the graphical user interface in FIG. 2-3 form no part of the claimed design.

1 Claim, 3 Drawing Sheets
